UNITED STATES PATENT OFFICE.

HERMANN LEMP, OF LYNN, MASSACHUSETTS, ASSIGNOR TO ELIHU THOMSON, OF SWAMPSCOTT, MASSACHUSETTS.

SUPPORT FOR MOTORS OF SELF-PROPELLED VEHICLES.

SPECIFICATION forming part of Letters Patent No. 692,880, dated February 11, 1902.

Application filed November 1, 1901. Serial No. 80,734. (No model.)

To all whom it may concern:

Be it known that I, HERMANN LEMP, a citizen of the United States, residing at Lynn, county of Essex, State of Massachusetts, have 5 invented certain new and useful Improvements in Supports for Motors for Self-Propelled Vehicles, (Case No. 2,420,) of which the following is a specification.

In connection with self-propelled vehicles 10 it is important that the motors be suspended in such a manner that the various operating parts are readily accessible, so that in case of repair they may be removed without taking the motor as a whole from the vehicle.

15 The object of the present invention is to provide a motor suspension which is simple in construction, permits of the necessary adjustment of the motor as a whole, and enables the working parts to be removed without disturbing the stationary frame or changing its position relative to the driving-shaft or axle.

The scope of my invention will be more fully set forth in the description and in the claims appended thereto.

25 In the accompanying drawings, which illustrate an embodiment of my invention, Figure 1 is a side elevation of a vehicle-frame. Fig. 2 is a plan view thereof. Fig. 3 is a detail enlarged view, partially in section, of the motor viewed from the end opposite the crank and also of the means employed for supporting the same from the vehicle-frame. Fig. 4 is an enlarged detail view of the hanger as viewed from the crank end of the motor. Fig. 30 5 is a side elevation of the motor and the supports therefor. Fig. 6 is a detail view of the outer supporting member or ring. Figs. 7 and 8 are respectively a front and side elevation of the inner supporting member. Fig. 9 35 is an enlarged sectional view of the hanger employed to support the transversely-extending frame-bars. Fig. 10 is a longitudinal section of the engine. Fig. 11 is a section taken on line 11 11 of Fig. 10, and Fig. 12 is a section taken on line 12 12 of Fig. 10.

In the drawings, 1 represents a rectangular vehicle-frame, preferably made of wood, and is supported from the front axle by means of half-elliptic springs 2 and from the rear axle 40 by full-elliptic springs 3. Extending across the frame are two parallel tubes or rods 4 and

5, which are supported at the ends by hangers 6 and 7. The rods are employed to support the motors, which in the present instance take the form of engines, as will appear hereinafter. The hangers are held in place by bolts that extend vertically through the side bars of the frame. Each hanger consists of a flat plate 8, Fig. 9, which rests on the upper surface of the wooden frame-bar, and a plate 60 that extends downward and at right angles thereto and is provided with two projections 9, the latter being secured to the frame-bar by screws or bolts. By separating the projections a certain distance, as shown, Figs. 1 and 4, the 65 front head of the engine can be removed without disturbing the hanger. The lower end of each projection is provided with a socket 10, Figs. 5 and 9, and mounted in these sockets are the transversely-extending tubes 70 which support the motors. In the end of each tube is a plug 11, which is retained in place by a pin 12. The tube is held in the socket by a bolt 13, the latter entering the plug 11. The transversely-extending tubes 75 being supported at the ends in hangers 6 and 7 (the latter being rigidly secured to the frame-bars) act as a brace for the center portion of the frame in addition to supporting the motors.

80 In the present instance the motor consists of a three-cylinder single-acting engine, although the particular form of motive device may be varied as desired. The cylinders are displaced by one hundred and twenty degrees, and one of the cylinders extends upward vertically between the frame-bars 4 and 5. The engine is provided with a front detachable head 14, carrying the bearing for the crank-shaft, and is secured to the main frame 90 by bolts 15. Between the detachable head and the main frame is a supporting means 16, made in the form of a ring of the character illustrated in Fig. 6. The ring is provided with a shouldered portion 17, as indicated in 95 dotted lines, Fig. 6, and in full lines in the sectional view Fig. 10. This shouldered portion engages with a seat formed in the main engine-casing and takes the strain off of the retaining-screws and also off of the bolts 100 which clamp the head to the frame. The ring as a whole is secured to the engine-frame

by screws 18, Fig. 10, so that the engine will be supported when the head 14 and its retaining-bolts are removed. Since the bolts for securing the head to the engine-frame also 5 pass through the ring, an additional means is provided for holding the parts together, which is important where the parts are subjected at times, as in the present instance, to great strain. The ring is provided with a 10 pair of split bosses 19, located on opposite sides, which bosses are adapted to receive the parallel and transversely-extending frame-tubes and support the engine. After the engine is mounted in the proper position each 15 boss is firmly clamped to the tube by the bolt 20, which passes through ears formed thereon. To maintain a fixed distance between the rear driving-axle 31 and the engine or crank shaft 21 for the purpose of keeping 20 the gears in proper adjustment or the tension on the chain a fixture, it is necessary to provide a connecting device. Such a device is found in the connecting-rod 22, which is pivotally secured to the rear axle by a pivotal 25 connection 23 and to the engine-frame by a pivotal connection 24. The last-mentioned connection consists of a fork which surrounds the lug 25, Fig. 6, on the supporting-ring on two sides, and extending through the fork and 30 the lug is a bolt for holding the parts together. This arrangement permits the vehicle-frame as a whole to move up and down without altering the tension of the sprocket-chain 26. The chain extends between a sprocket-wheel 35 27 on the rear wheel and a sprocket 28 on the main shaft of the engine. Inasmuch as certain of the engines will be used on the left-hand side and certain of the others on the right-hand side of the frame, the pattern for 40 the ring or supporting means 16 is provided with two lugs 25. In Fig. 6 one of these lugs is shown in full lines, while the other is shown in dotted lines, thus indicating that the one not in use has been cut off. If desired, both 45 of these lugs may be left on the finished part, as indicated in Fig. 1. As the shoulder 17 on the ring is made in finishing the ring, it does not have to be considered in the pattern or casting other than to provide sufficient 50 stock.

As it is only necessary to remove one head, and that the front one, for the purpose of inspection or repair, the rear head, or one back of the crank-shaft, is provided with split 55 bosses 29, Figs. 7 and 8, which surround the parallel frame-tubes 4 and 5. If it be deemed advisable, the rear of the engine may also be provided with a ring-like support of the character illustrated in Fig. 6, in which case the 60 split bosses would be omitted from the rear head. The head is secured to the tubes 4 and 5 by bolts 30, which pass through ears formed on the split bosses. The rear head is shown in elevation in Fig. 7, and the center thereof 65 is bored out at 32 to receive the shaft 33, the latter being employed to adjust the cut-off cams controlling the admission of steam to

the cylinders. The head is secured to the engine-frame by bolts 34.

Each motor is entirely supported by the 70 two transversely-extending tubes or rods 4 and 5, and the latter are supported by the end hangers 6 and 7. It will be seen that by this construction the motors as a whole may be shifted toward or away from each other 75 in order to laterally adjust the position of the driving-sprocket 28 with respect to the rear sprocket 27. The tension on the chain can be adjusted by the connecting-rod 22.

Referring to Fig. 10, the advantages of the 80 novel construction described will be apparent. 1 represents the wooden frame-piece, and 7 the hanger mounted thereon for supporting the transversely-extending tubes. The front of the engine is supported by the shouldered 85 ring 16 and the rear by the rear head. 40 represents the cylinders, and 41 the pistons moving therein, the latter being connected to the crank in a suitable manner. In the present instance roller-bearings 42 are employed 90 to reduce the friction. The crank-pin is perfectly straight, so that it may be moved longitudinally into and out of the bearing for the purposes of assembling or removing the parts. The end of the crank-shaft is elongated at 43 to drive the cam 44. The latter is rigidly mounted on the shaft 33, and as it moves to and fro the period of steam admission is varied.

Surrounding the crank-shaft 21 and retained in place by the crank-arm on the inner end and by the disk 45 on the outer end is a sleeve 46. The sleeve is provided with a bearing 46'. This arrangement is a desirable one, for when the parts are worn a new sleeve and 105 bearing may be inserted in place at a small cost, whereas the cost of a new crank would be considerable. The bearing is slotted in the under side to receive a piece of felt or similar material 47 to insure proper lubrication. The upper part of the bearing is provided with two ribs 48, which with the end flanges of the bearing form an oil-well. Oil or other lubricant is admitted through the covered opening 49 and feeds by gravity through 110 the holes 50 into the oil-groove in the bearing. The crank-shaft with its extension 43 and the bearing 46 are removable with the head, so that the working parts can be taken from or returned to the engine by a single operation. 115

Assume, for example, that it is desired to inspect the interior of the motor for the purpose of repair or otherwise. The chain 26 is detached and the nuts removed from the bolts 15, after which the head 14, crank-shaft 21, 120 and driving-sprocket 28 may be removed without in any way interfering with the motor adjustment or suspension. Since the connecting-rod 22 is secured to the ring 16, which in turn is secured to the frame and to the rear 125 axle, the parts may be returned to place without in any way altering the adjustment. If it is necessary to shift the engine laterally in order to bring the driving and the driven sprockets

into the same vertical plane, the bolts passing through the split bosses are loosened and the engine as a whole shifted either toward or away from the frame-bar, as desired. In Fig. 5 the engine is shown as being in the extreme left-hand position and the bosses are in engagement with the sockets 10.

I have shown two motors on the vehicle, as this arrangement possesses certain features of advantage; but I may use one motor and support it in the manner described either at one side or at a point between the side bars of the frame. With one motor the usual driving connection would be employed.

5 What I claim as new, and desire to secure by Letters Patent of the United States, is—

1. In a vehicle, the combination of longitudinal bars, a transverse frame-bar, hangers for supporting the transverse bars from the longitudinal bars, a motor having a detachable head, a driving-wheel, gearing between the motor-shaft and the wheel, and means located between the gear and the body of the motor for adjustably supporting the motor on 25 the transverse bar.

2. In a vehicle, the combination of a pair of longitudinal frame-bars, a pair of transversely-extending frame-bars, hangers for securing the longitudinal and transverse frame-bars together, a motor having a detachable head, supporting devices secured to the motor and arranged to engage with both of the transverse bars, a driving-wheel, and gearing between the motor and the wheels.

3. In a vehicle, the combination of a pair of longitudinal frame-bars, a pair of transversely-extending frame-bars, a pair of hangers mounted on the longitudinal bars, each hanger having two sockets for receiving the transverse rods, a motor having a detachable head, means adjustably secured to the transverse frame-bars and to the motor-casing for supporting the motor, a driving-wheel, an axle therefor, chain-gearing between the engine and the wheel, and a connecting-rod between the engine and the axle for maintaining a given tension on the chain.

4. In a vehicle, the combination of longitudinal frame-bars, transverse frame-bars, an engine which extends between the transverse frame-bars, detachable supporting members for the engine which are rigidly secured thereto, and means whereby the members are adjustably secured to both of the transverse frame-bars.

5. In a vehicle, the combination of a frame, a pair of motors, a transversely-extending frame-bar forming a support common to the

motors, means whereby each motor may be adjusted laterally independent of the other, 60 an axle, springs between the axle and the frame, connecting-rods between the axle and each motor whereby the position of the axle with respect to a motor may be independently adjusted, wheels mounted on the axles 65 for driving a common load, and gearing between the motors and the wheels.

6. In a vehicle, the combination of a frame composed of longitudinal and transverse bars, a motor having a detachable head, a supporting member for the motor comprising a ring having bosses through which the transverse bars extend, and means for securing the ring to the motor.

7. In a vehicle, the combination of a frame 75 composed of longitudinal and transverse bars, a motor having a detachable head, a supporting-ring having bosses through which the transverse bars extend, means for securing the ring to the motor, and means for securing the head to the motor which also passes through the ring.

8. In a vehicle, the combination of a frame, a pair of transversely-extending frame-bars, a motor having detachable heads, one of said 85 heads being provided with bosses through which the bars extend, a detachable ring also having bosses through which the frame-bars extend, and means for securing the ring to the motor.

9. In a vehicle, the combination of a frame, a pair of transversely-extending bars, a motor, a ring for supporting one end of the motor which is provided with a pair of bosses through which the bars extend, and a lug, a 95 driving-wheel, an axle therefor, gearing between the driving-wheel and the motor, and a connecting-rod extending between the axle and the lug on the ring.

10. In a vehicle, the combination of transversely-extending frame-bars, a motor having a pair of detachable heads, a ring for supporting one end of the motor having a shouldered portion which closely fits the motor-casing, bosses formed on the ring through 105 which the frame-bars extend, means for securing the ring to the casing, and means which pass through the head and the ring for securing the head to the casing.

In witness whereof I have hereunto set my hand this 26th day of October, 1901.

HERMANN LEMP.

Witnesses:

BENJAMIN B. HULL,
HELEN ORFORD.
